UNITED STATES PATENT OFFICE

2,633,246

HAT SUPPORTING HOOK

James E. Guthrie, Kansas City, Mo.

Application September 22, 1947, Serial No. 775,418

2 Claims. (Cl. 211—32)

1

This invention relates to hat supporters or hooks and has for its object to provide means adapted for suspension from a wall or vertical surface for the support of men's hats in particular in such fashion that the hat is pendent or rockingly carried by the crown and the brim is perfectly protected against any load or pressure tending to press it from its proper blocked position in relation to the crown of the hat. The device of the invention preserves the shape of the hat even more perfectly than when the hat is placed on a shelf or horizontal support which nearly always imposes some weight on the brim of the hat.

A further object of the invention is to produce a device of the character indicated which is of strong, durable, efficient and inexpensive construction; and in order that it may be fully understood, reference is to be had to the accompanying drawing, in which:

Figure 1 is a side elevation showing the hook or support of the invention with a hat in partial vertical section carried by said hook.

Fig. 2 is a rear view of the suspension hook and hat with the hat in section on the line II—II of Fig. 1.

Fig. 3 is a perspective view of the sustaining hook of the invention; and,

Fig. 4 is a perspective view of a modified form of my invention.

In the form shown by Figs. 1 to 3 inclusive, 10 is a supporting loop or any suitable character adapted to be detachably or permanently secured to a wall or other supporting surface. The form of the device here shown is made of a single length pliable wire and is intertwisted from one end of loop 10 as at 12. The two wires then diverge downwardly parallel to the plane of the supporting wall as at 14 and have lower intermediate portions 16 extending substantially horizontally outward away from the wall.

The ends of portions 16 then converge upwardly in relation to each other and outwardly in relation to the plane of the wall as at 18. The upper ends of the portions 18 terminate in rockers, loops or eyes 20 to rockingly engage the crown of a hat 22 as shown in Figs. 1 and 2. In this connection, it is to be noted that the converging relation of the two portions 18 accommodate the top crease 24 or other indentation in the crown of the hat.

In the form shown in Fig. 4, a flat plate 100 is shown to be polygonal but may be cut to any desired configuration and is provided with a pair of openings 102 for receiving screws or the like. Such mounting means makes it possible to secure

2

the hat rack of this embodiment flatly against a vertical wall or the like.

A pair of shaped apart arms having horizontal portions 104 and vertical portions 106 extend laterally from one face of the plate 100. These arms terminate at the free end of their portions 106 in a loop 108. Any suitable means of fastening of the free ends of the portions 104 may be used such as embedding the same into plate 100. A boss 110 on each arm disposed flatly against the face of plate 100 serves to add support. A hook 112 extending downwardly and outwardly from plate 100 near its lowermost edge and preferably midway between portions 104 of the hat supporting arms serves as a coat hanger or hanging means for other wearing apparel.

With hat supports embodying the constructions shown and described, it will be apparent that a hat is pendently carried by the crown with no load of any kind on the brim, and that a hat will balance itself in accordance with its center of gravity. From the above description and drawing it will be evident that I have produced hat supports embodying all the features of advantage set forth as desirable, and while I have described and illustrated two preferred embodiments, it is to be understood that I reserve the right to make all changes within the spirit and scope of the appended claims.

Having thus described the invention, what is claimed as new and desired to be secured by Letters Patent is:

1. A hat hanger comprising a pair of spaced-apart, elongated, upstanding members, each having a normally uppermost end; a hat-engaging rocker eyelet forming said uppermost end of each member respectively; and means connected to said members and adapted for mounting on an upright surface for supporting the members with the rocker eyelets in a common horizontal plane spaced from said surface a distance greater than the height of a hat, said rocker eyelets being spaced and the distance therebetween being greater than the width of an elongated crease in the crown of said hat, whereby to clear said crease when the hat is placed on the hat hanger in resting engagement with the rocker eyelets only, with both of said rocker eyelets disposed within the hat in contacting relationship therewith solely at the point of merger between the side wall and top of the hat crown, and with said crease disposed vertically.

2. A hat hanger comprising a single length of wire provided with a mounting loop at the right thereof; a pair of spaced lengths depending from

said loop; a portion extending horizontally from the lowermost end of each length respectively; an upright leg on that end of each portion respectively remote from said lengths; and a hat-engaging rocker eyelet on the uppermost end of each leg respectively, said rocker eyelets being in a common horizontal plane spaced from said lengths a distance greater than the height of a hat, said rocker eyelets being spaced and the distance therebetween being greater than the width 10 of a crease in the crown of said hat, whereby to clear said crease when the hat is placed on the hat hanger in resting engagement with the rocker eyelets only and with both of said rocker eyelets disposed within the hat in contacting relationship 15 therewith solely at the point of merger between the side wall and top of the hat crown, and with said crease disposed vertically, each leg diverging outwardly away from said lengths as the rocker eyelets are approached and the legs converging 20

relatively as the rocker eyelets are approached whereby the hat is balanced by the hat support when on the rocker eyelets.
